(57) **CLAIM**

We claim the ornamental design for a throwing dart toy, as shown and described.

DESCRIPTION

FIG. 1 is a perspective view of a throwing dart toy showing our new design, the view from the opposite side being a mirror image.

FIG. 2 is a side elevational view of the throwing dart toy of FIG. 1, the opposite side being a mirror image; and,

FIG. 3 is a rear end elevational view taken from the left in FIG. 2.
